(57) **CLAIM**

The ornamental design for a sandpaper dispensing device, as shown and described.

DESCRIPTION

FIG. 1 shows a top and side perspective view of the sandpaper dispensing device.

FIG. 2 shows a first side elevation view thereof.

FIG. 3 shows a second side elevation view thereof.

FIG. 4 shows a third side elevation view thereof.

FIG. 5 shows a fourth side elevation view thereof.

FIG. 6 shows a top plan view thereof.

FIG. 7 shows a bottom plan view thereof.

FIG. 8 shows the top side perspective view of FIG. 1 with the device opened.

FIG. 9 shows a top plan view thereof; and,

FIG. 10 shows a side elevation view thereof.

FIGS. 8, 9, and 10 are provided to show the contours of the depth of the sandpaper dispensing device of FIGS. 1-8.

1 Claim, 8 Drawing Sheets
